UNITED STATES PATENT OFFICE.

JOHN H. GASSAWAY, OF WASHINGTON, DISTRICT OF COLUMBIA,
ASSIGNOR TO GEORGE A. REACH, OF PHILADELPHIA, PENN-
SYLVANIA.

BASE-BALL GLOVE.

No. 839,063.

Specification of Letters Patent.

Patented Dec. 18, 1906.

Application filed February 9, 1906. Serial No. 300,240.

To all whom it may concern:

Be it known that I, JOHN H. GASSAWAY, a citizen of the United States, residing at Washington, in the District of Columbia, have invented certain new and useful Improvements in Base-Ball Gloves; and I do hereby declare the following to be a full, clear, and exact description of the invention, such as will enable others skilled in the art to which it appertains to make and use the same.

This invention relates to base-ball gloves, and especially to the mitts used by players other than the catcher.

The chief object of said invention is to greatly increase the size of the pocket in gloves of this character and also to improve the glove as a whole by providing it with better means of attachment to the wrist of the player and with improved means for deadening the impact of the ball when caught therein.

To these ends my invention consists in the construction and combination of parts hereinafter more particularly set forth and claimed.

In the accompanying drawings, Figure 1 represents a view of a glove embodying my invention, showing the inner or palm side thereof; and Fig. 2 is a similar view of the same, showing, partly in section, the opposite side of said glove.

A designates the body or palm of the glove, B the spreader-bar embedded in the rear part of the padding thereof, and C a wristband or strap attached at one point to the rear edge of said body. This body A is constructed in the following novel manner. Instead of padding the whole palm, as has heretofore been done, I provide a very heavy pad A' at the sides and rear end of said body and leave the center entirely unpadded. Said heavy pad at the sides and rear keeps the front and back walls of the glove-body apart, and thus creates a large air-chamber or air-cushion exactly at the point where the impact is greatest. The leather wall or face a on the inner or palm side of the glove is made as inelastic as possible in order to decrease any tendency the ball may have to rebound upon impact. Such impact will drive in wall a, even if exceedingly inelastic material be used, compressing the air in said air chamber or cushion. The cushioning effect of

this sudden compression of the air therein is of course very great and takes up far the greater part of the jar and strain incident to such catching. As the wall a recedes under the blow of the ball it will of course cause the sides of the pocket to contract, enabling the player to make a surer catch. This pocket has occupied but a small fraction of the inner surface of the base-ball gloves heretofore made and used. To greatly increase the size and efficiency of said pocket is the chief aim of the present invention. For this purpose I employ my spreader-bar B in connection with a loop X and wristband or other means of one-point attachment to the wrist of the player. Said bar is preferably a straight metal or whalebone rod embedded in the center of the rear pad of the body, as shown, running clear through from side to side thereof and holding that end of the glove perfectly flat. This spreads the rear corners of the glove far apart, permitting a great increase in the size of said pocket. Said rod is prevented by the heavy padding in which it is embedded from injuring the hand or wrist of the wearer.

Ordinarily in gloves of this class the wrist attachment consists of a strap or lacing extending from corner to corner of the rear end thereof, across the back of the wearer's wrist. This of course pulls the corners of the glove partly together, distorting the body of said glove and greatly decreasing the size and utility of said pocket. My spreader-bar alone if used with such a strap would of course tend to overcome this objection; but I prefer to employ my means of one-point attachment to the wrist. Said means consists of a wristband or strap C passing through a loop X on the rear end of the body of the glove at a point approximately in the middle of the spreader-bar. By this construction I provide doubly against contraction of the pocket through use, as my spreader-bar holds the rear end of the glove positively extended, and my one-point attachment to the inner side of the wrist of course does away with the main cause of such contraction. I may also dispense entirely with any sort of fastening or strap at the wrist, as the covering for the back of the hand, as shown in Fig. 2, extends much farther up

than is usual in this class of gloves and holds the glove in proper position, the rear arm b' of pad or roll A' fitting snugly at the base of the wrist just above the heel of the hand. 5 This latter form without any wrist-strap or other attachment is simpler, cheaper to manufacture, and in practical use has been found very satisfactory.

The pad A' is usually formed in three integral branches or arms—two side arms a' c' , arranged one along each side edge of the glove-body, and the third arm b' , arranged along the rear or upper edge of said body and at right angles to the other arms a' and c' .

15 Having thus described my invention, what I claim as new, and desire to secure by Letters Patent, is—

1. A base-ball glove provided with an air-space in the body thereof in combination 20 with padding surrounding said space and a spreader-bar extending through one side of said padding for the purpose set forth.

2. In a base-ball glove, an air-cushion in the palm thereof in combination with a spreader-bar at the rear end of the glove, 25 adapted to keep the said rear end extended and thereby prevent any decrease in the size of the cushion of said glove, and means for attaching one point of said rear end to the player's wrist substantially as set forth. 30

3. In a base-ball glove, pad A' and spreader-bar B, embedded in the rear arm b' of said pad and adapted to keep the same extended in a straight line, in combination with wrist-strap C, attached at one point 35 only to the rear end of said glove substantially as set forth.

In testimony whereof I have signed my name to this specification in the presence of two subscribing witnesses.

JOHN H. GASSAWAY.
